UNITED STATES PATENT OFFICE.

SEYMOUR L. GUTHORN, OF NEW YORK, N. Y., ASSIGNOR TO VACUUM ENGINEERING COMPANY, OF NEW YORK, N. Y., A CORPORATION OF NEW YORK.

PNEUMATIC CLEANING IMPLEMENT.

1,072,607.

Specification of Letters Patent.

Patented Sept. 9, 1913.

Application filed July 26, 1911. Serial No. 640,587.

To all whom it may concern:

Be it known that I, SEYMOUR L. GUTHORN, a citizen of the United States, residing in the city, county, and State of New York, have 5 invented certain new and useful Improvements in Pneumatic Cleaning Implements, of which the following is a full disclosure.

My invention relates to that class of pneumatic cleaning implements adapted to be 10 moved over the surface to be cleaned, and in which a suction is created by means of any suitable apparatus, in order that dirt and air may be drawn from the floor or surface being cleaned, into the implement, and 15 carried away through suitable pipes or conduits.

The objects of my invention are to provide an implement of few parts, simple in construction, cheap to manufacture, and so 20 constructed and arranged that, while the head is in operative position, the handle may be made to assume any and all angles necessary to work beneath obstructions such as benches and desks in school rooms, and 25 yet that the operator may rotate the suction head upon the floor in whatever position the handle may be, by twisting the handle. I accomplish these objects by a combination of parts.

30 The preferred embodiment of my invention is shown in the drawing accompanying and forming a part of this specification.

In this drawing Figure 1 is a side elevation of a cleaning implement embodying 35 my improvements, the handle being broken away. Fig. 2 is a sectional view taken on the line 2—2 of Fig. 1. Fig. 3 is a transverse sectional view of the structure shown in Fig. 1 taken on the line 3—3 of that figure. 40 Figs. 4, 5 and 6 are detail views showing modified suction heads.

Referring in detail to the structure shown in Figs. 1, 2 and 3, the numeral 1 designates the base of the suction head which has felt 45 pads 2 secured to its lower surface. A threaded ring 3 is mounted on the socket element 4, secured to the base 1. The ring 3 and socket element 4 together form a socket 5, in which is secured the spherical 50 head or enlargement 6 attached to the handle 7. A suction orifice 8 is centrally located in the bottom of the suction head and opens into the conduit 9 which is fixed to the base and extends up into the spherical head 6. 55 Pins 10 are secured to the conduit 9 on oppo-

site sides and engage slots 11 formed on the inner side of this spherical head 6. The combination of parts forming the joint between the handle and the suction head is such that the handle of the device can be inclined in any direction with respect to the suction head without disturbing the proper position of the head on the floor, and by means of the pins 10 in the slots 11 the suction head is prevented from twisting with 60 respect to the handle but the suction head can be rotated on the floor by twisting the handle 7 in whatever position the handle may be. The members 3 and 4 form with the spherical head 5 a ball-and-socket joint 65 which can always be adjusted or taken apart by adjusting or removing the member 3, which has a screw threaded engagement with the member 4.

The suction orifice 8 formed in the bottom 75 of the suction head, communicates with two suction conduits 12 which open outwardly on opposite sides of the suction head. The outer ends or openings of the conduits are substantially as wide as the head is long, 80 and when the head is moved along the floor all particles of chalk and the like will enter the enlarged openings and be guided by the inclined walls 16 of the conduits to the orifice 8. The oppositely disposed conduits 17 85 have their outer ends closed and are intended to pick up the fine particles of dust which pass under the head as it is moved along.

In Fig. 4 the construction is the same as 90 that above described, so far as the joint is concerned. The suction head is made square in shape and the suction conduits 12^a extend to two opposite corners of the device. This shape and arrangement of conduits is ad- 95 vantageous in some instances when used with my improved implement, particularly where it is desired to remove dirt and dust from among chairs, furniture and similar articles. In the construction shown in Fig. 5 the suc- 100 tion head is made triangular and the central suction orifice 8 communicates by three sepa- rate suction conduits 12^b with three enlarged openings 13^b located adjacent to the points of the triangular base. In Fig. 6 the suc- 105 tion head is octagonal in shape, and there are four dust slots or suction conduits 12^c which terminate at their inner ends in a central suction orifice 8, and at their outer ends in enlarged openings 13. The relation of 110

the enlarged openings 13^a and the sides 14 of the head is such that as the suction head is moved along the floor, a particle will either enter one of the enlarged openings 5 13^a in the first instance or else will strike one of the inclined edges 14 and be forced along the edge until it arrives opposite one of the enlarged openings 13^a, so as to then be drawn through the suction or dust conduit 10 12^a into the central orifice and removed in the usual way.

The operation of the device with the suction head shown in Figs. 1, 2 and 3, or either of the modifications shown in Figs. 4, 5 and 15 6, is as follows: The suction head is placed on the floor to be cleaned by the operator who controls the position of the device by means of the handle 7, and moves it over the floor. The dust and dirt are drawn in 20 through the dust conduits 12, 12^a, 12^b, 12^c into the central orifice and then out through the conduit 9 and the hollow handle of the device. The ball-and-socket joint permits the operator to incline the handle as shown at 19 25 and 20 in Fig. 1, or 21 in Fig. 3, or in any other inclined position which may be desired. This makes it possible to conveniently and speedily insert the device beneath benches and pieces of furniture, and therefore to reach accumulations of dirt under 30

such articles which it would not be possible to reach with a device having a fixed handle, or having a handle adapted to move in only a single plane. Not only can the device be inserted as above described, but the suction 35 head may be rotated while the handle is inclined, by merely twisting the handle.

I do not claim herein the improved arrangement of suction conduits or slots shown on the lower face of the suction head but 40 have claimed such matter in my pending application Serial No. 662,279.

What I claim is:

1. The combination in a device of the kind described, of a suction head and a hollow 45 handle connected therewith by a ball-and-socket universal joint, substantially as described.
2. The combination, in a device of the kind described, of a suction head and a 50 handle connected therewith by a ball-and-socket universal joint, and means for preventing said handle from being rotated about its axis with respect to said head, substantially as described.

SEYMOUR L. GUTHORN.
